D. G. BLATTNER

CIRCUIT FOR HEATING THE FILAMENTS OF AUDIONS

Filed Oct. 4, 1920

Inventor:
David G. Blattner.
by W. Beatty. Atty.

UNITED STATES PATENT OFFICE.

DAVID G. BLATTNER, OF BOGOTA, NEW JERSEY, ASSIGNOR TO WESTERN ELECTRIC COMPANY, INCORPORATED, OF NEW YORK, N. Y., A CORPORATION OF NEW YORK.

CIRCUIT FOR HEATING THE FILAMENTS OF AUDIONS.

Application filed October 4, 1920. Serial No. 414,449.

To all whom it may concern:

Be it known that I, DAVID G. BLATTNER, a citizen of the United States, residing at Bogota, in the county of Bergen, State of New Jersey, have invented certain new and useful Improvements in Circuits for Heating the Filaments of Audions, of which the following is a full, clear, concise, and exact description.

10 In White Patent No. 1,195,632 it is shown how a source of alternating currents may be employed for heating the filamentary cathode of an electron discharge device without introducing into the circuit fluctuations of a frequency corresponding to the cathode heating frequency. According to that arrangement, the grid and anode electrodes are connected to the midpoint of the secondary winding of the transformer which 15 connects the heating source to the cathode. In applying this arrangement to a plurality of electron discharge devices, a separate transformer winding having a midpoint connection is provided for the cathode of 20 each tube according to the disclosure in the patent.

According to the present invention, the fluctuations of the cathode heating frequency are suppressed without necessitating 25 the use of a transformer, and consequently without requiring that a connection be made to the midpoint of a transformer winding. Furthermore, instead of employing a compensating circuit which is individual to each 30 cathode, as in the patent, the present invention provides a compensating circuit which is common to a plurality of vacuum tubes. In case it is desired to apply the arrangement to a push-pull tube circuit 35 wherein two tubes are connected in opposition in the same circuit, an impedance may be connected in shunt to the two cathodes, taps being taken from the midpoint of this 40 impedance to the anode and control electrodes. When the connections are made in this way the average difference of potential 45 at any instant between different portions of the cathodes and the grids and anodes, due to the heating currents, will be zero and consequently no objectionable tone or noise 50 is introduced into the circuit due to the use of alternating currents for heating the cathodes.

This will be described in connection with 55 the drawings, which show diagrammatically

a repeating circuit embodying one form of the invention.

Referring in detail to the drawings, there is connected between the incoming line 1 and the outgoing line 2, by means of transformers 3 and 4, a push-pull vacuum tube device comprising the electron discharge tubes 5 and 6, which are adapted to repeat and amplify the alternating currents applied to line 1. If desired, a potentiometer 60 7 may be employed in the line 1. The vacuum tube 5 comprises a cathode 8, an anode 9, and a control electrode 10, and the vacuum tube 6 contains similar electrodes identified by corresponding numbers primed. 65

The filamentary cathodes 8 and 8' are adapted to be heated by a source 11 of direct current when the switch 12 is in the position shown. Preferably the cathodes are heated by a source 13 of alternating 75 currents which is connected, when the switch 12 is in its alternate position, to the impedance 14, preferably or conveniently a resistance, in shunt to which are connected the filaments 8 and 8'. The 80 midpoint of the impedance 14 is grounded at 15 in order to complete a circuit through ground 16, battery 17, and the halves of the secondary winding of transformer 3 to the two grids 10 and 10'. The anode 85 circuits are completed through the halves of the primary windings of the transformer 4 and the space current battery 18 to the midpoint connection of impedance 14. The amount of current flowing to the two filaments may be adjusted by the variable 90 resistance 19 without interfering with the compensating connection. If desired the resistance 19 may be connected between 95 transformer 20 and source 13 instead of in the secondary circuit of this transformer as shown.

In wave repeating and amplifying systems where high amplification is secured, it 100 is desirable to ground the cathode of the repeater in order to reduce the capacity to ground of the connecting wires and thereby prevent singing of the repeater. The present invention provides a symmetrical path to ground for each repeater whereby the 105 ground connection does not interfere with the circuit employed to suppress the fluctuations which tend to be present due to the use of alternating currents for heating the cathodes.

If desired, the compensating grounded connection may be used in connection with a plurality of sets of push-pull repeaters such as shown connected in tandem, i. e., 5 the out-going line 2 may include one or more vacuum tube repeaters such as shown.

Each of the tubes of the push-pull amplifier substantially prevents the alternations of heating current in the cathode of 10 the other tube from causing current variations in the output circuit of the amplifier, whether or not the connections of the grids and anodes of the tubes to the cathodes are made in such manner that the average difference of potential at any instant between 15 different portions of the cathode and the grid and anode of either tube due to the heating currents, is zero; for at any instant when the heating current would increase the average 20 difference of potential between the cathode and the grid or the anode of one of the tubes, the heating current would increase the average difference of potential between the cathode and the grid or the anode of the 25 other tube. However, the connection of the grids and the anodes to the midpoint of the impedance 14 is desirable for overcoming any lack of compensation due to lack 30 of symmetry or balance between the two halves of the push-pull circuit.

Although the invention is set forth particularly with reference to a push-pull amplifier employing two tubes, it is to be understood that a single tube may be used instead, 35 after the fashion disclosed, for instance, in the patent to E. H. Colpitts, No. 1,128,292, February 16, 1915, entitled "Electrical wave amplifier."

What is claimed is:

- 40 1. In a wave repeating and amplifying system, the combination of electron discharge devices each having a cathode and an anode connected in opposition, a source of alternating currents for heating said cathodes, and a compensating circuit common to said cathodes, for preventing the alternation in the cathode heating currents from causing current variations in the output circuits of said devices.
- 45 2. A push-pull vacuum tube circuit comprising electron discharge devices connected in opposition and having a cathode and an anode a source of alternating currents for heating said cathodes, an impedance in shunt to said cathodes, a connection from an intermediate point of said impedance to said anodes, and a connection from an intermediate point of said impedance to ground.
- 50 3. A wave repeating and amplifying system comprising an incoming line, an outgoing line, a plurality of electron discharge devices connected therebetween and each having a cathode, an anode and a control electrode, a transformer between said discharge devices and each of said lines, a source of

alternating currents for heating said cathodes, an impedance in shunt to said cathodes, and a connection from an intermediate point of said impedance to each of said transformers.

4. In a wave repeating and amplifying system, the combination of electron discharge devices each having a cathode and an anode connected in opposition, a source of alternating currents for heating said cathodes, and a compensating circuit common to said cathodes, for preventing the alternations in the cathode heating currents from causing current variations in the output circuits of said devices, said compensating circuit comprising an impedance in shunt relation to each of said cathodes.

5. An electric wave repeating apparatus comprising divided input and divided output circuits, means including a hot cathode 85 for producing two ionized streams, said streams being oppositely included in said output circuit, means for supplying cyclically varying heating current to said cathode, and two electrodes for controlling said ionized streams respectively and oppositely connected in said input circuit.

6. An electric wave repeating apparatus comprising divided input and divided output circuits, means for producing an ionized stream included in each division of said output circuit, said means including hot cathode means, electrodes, one in each division of said input circuit for controlling said ionized streams respectively, and means 95 for supplying cyclically varying heating current to said cathode means.

7. In an electric wave repeating apparatus, the combination with input and output circuits, of two hot cathode electron discharge repeater elements oppositely connected in said circuits whereby one of said elements is adapted to repeat certain parts, and the other, the remaining parts of said input waves, and means for supplying cyclically varying heating currents to the cathodes of said repeater elements.

8. In combination, an incoming circuit, an outgoing circuit, and a circuit for transferring indications from the first to the second of said circuits comprising an electric discharge device having a cathode, an anode, and an anode circuit, a source of alternating current for heating said cathode, said anode circuit being inductively coupled to said outgoing circuit, and a second electric discharge device having a cathode heated from said source of alternating current and an anode circuit inductively coupled to said outgoing circuit in opposition to the first 115 mentioned anode circuit.

In witness whereof, I hereunto subscribe my name this 29th day of September A. D., 1920.

DAVID G. BLATTNER.

DISCLAIMER

1,483,273.—*David G. Blattner*, Bogota, N.J. CIRCUIT FOR HEATING THE FILAMENTS OF AUDIONS. Patent dated February 12, 1924. Disclaimer filed June 24, 1933, by the assignee, *American Telephone and Telegraph Company*.

Hereby enters this disclaimer to claims 6 and 8 of said Letters Patent, to wit:

“6. An electric wave repeating apparatus comprising divided input and divided output circuits, means for producing an ionized stream included in each division of said output circuit, said means including hot cathode means, electrodes, one in each division of said input circuit for controlling said ionized streams respectively, and means for supplying cyclically varying heating current to said cathode means.”

“8. In combination, an incoming circuit, an outgoing circuit, and a circuit for transferring indications from the first to the second of said circuits comprising an electric discharge device having a cathode, an anode, and an anode circuit, a source of alternating current for heating said cathode, said anode circuit being inductively coupled to said outgoing circuit, and a second electric discharge device having a cathode heated from said source of alternating current and an anode circuit inductively coupled to said outgoing circuit in opposition to the first mentioned anode circuit.”
